UNITED STATES PATENT OFFICE.

THOMAS J. COSTELLO, OF WARREN, OHIO, ASSIGNOR TO GEORGE J. HAGAN COMPANY,
OF PITTSBURGH, PENNSYLVANIA, A CORPORATION OF PENNSYLVANIA.

ANNEALING-FURNACE.

1,336,681.

Specification of Letters Patent. Patented Apr. 13, 1920.

Application filed December 29, 1916. Serial No. 139,527.

To all whom it may concern:

Be it known that I, THOMAS J. COSTELLO, a citizen of the United States of America, residing at Warren, in the county of Trumbull and State of Ohio, have invented certain new and useful Improvements in Annealing - Furnaces, of which the following is a specification.

This invention relates to improvements 10 in furnaces used for annealing metals, in which long pieces, as for instance steel plates, are inserted in one end and discharged at the other end, with the mechanical assistance of carrying rollers; and the 15 objects of my invention are, first, to greatly economize the operating cost by providing means for easily, quickly and cheaply renewing said rollers when requisite so to do; second, to reduce to a minimum the portions 20 of said rollers in contact with the heat of the interior of said furnaces and their annealing contents; and, third, to provide means for utilizing said rollers for equalizing the temperatures in opposite ends and 25 throughout said furnaces.

I attain those objects by the mechanism illustrated in the accompanying drawings, in which—

Figure 1 is a view of the interior of my 30 furnace taken lengthwise, partly in section and broken away at the rear end. Fig. 2 is a view partly in section, taken through the line A—A of Fig. 1. Fig. 3 is a side elevation of a roller; and Fig. 4 is an edge 35 elevation of the same.

Fig. 5 is a view of a hollow roller in section taken through the center of its hub; Fig. 6 and Fig. 7 are sectional views on planes indicated by the lines VI—VI and 40 VII—VII, Fig. 5.

Similar characters refer to like parts throughout the several views.

A furnace, F, is inclosed by side walls 1, 1; an arched roof 2; end walls 3, and a bottom 21, on base 4; all of refractory material.

Charging openings 14 for the reception 50 of the plates or other articles to be annealed are formed in the front end of the furnace. The charging openings are provided with suitable doors (not shown) as is the usual practice and suitable provision is made for heating the chamber, the fire box for such purpose being located adjacent to the front 55 end of the furnace as is the usual practice.

A series of channels are formed at right angles to the direction of movement of articles through the furnace, in the bed or hearth of the furnace and within these channels are arranged shafts 9 which are 60 mounted in bearings 15, suitably supported by the side walls of the furnace, a series of suitably spaced rollers 7 are carried by each of these shafts, the shafts being supported by their bearings so that only a small portion 65 of the rollers will project above the hearth of the furnace, as clearly shown in Figs. 1 and 2. While any suitable means may be employed for cooling the rollers, it is preferred that they may be formed with 70 passages therethrough having their inlets and outlets formed by the hubs 8 which are made hollow and are internally threaded for the reception of short pipe sections forming the shafts for the rollers. The end 75 sections of the shafts are connected respectively preferably through packing boxes to water supply pipes 18 and outlet pipes 18', as shown in Fig. 2.

The channels extend through the side 80 walls of the furnace and are made of transverse dimensions as to permit of the rollers being lowered thereunto and shifted along so as to permit renewal of the rollers when necessary. While the ports 26 at the ends 85 of the channels will be normally closed by brick work or in any other suitable manner so as to prevent the inflow of air, it is preferred to also place removal blocks 25 in the channels as shown in Figs. 1 and 2. 90 The channels intermediate the rollers are covered by arches 24 which serve to protect the shafts 9 from excessive heating.

As to the rollers, Figs. 3 to 7, the stream of cold water flowing in from pipe 18 and 95 out through pipe 18' (Fig. 2) enters each of the hubs 8, 8, through the shafts 9, 9, until it strikes a deflecting wall 27 and a dead end 27^a, (in each) whence it passes around through the chamber 28 and close to the 100 periphery thereof, until it meets the other side of the wall 27 at 27', whence it is forced against a second dead end, 27^b, near the center of the roller and oppositely faced to end 27^a and out through the opposite 105 hollow shaft portion 9; and in like course through all the rollers of that series, out to and through the exit pipe 18'.

In practice large steel (or other) plates of great length and breadth, as for steel 110

car or armor plate construction, are passed in to the opened port 14 and taken in and over the trains of rollers 7, 7, until inclosed in the furnace whose exit port is shut; 5 whereupon the entrance port 14 is closed.

The extreme heat of the front or charging end of the furnace tends to over heat the rollers 7, 7, at that end and to raise the temperature of the front end of the 10 furnace and the series of rollers nearest to it to a higher degree than that of the exit end and the rear rollers.

It is essential that the entire furnace should be kept at as nearly a uniform temperature as possible to produce a uniform 15 temper in the annealed metal. Wherefore, while I am aware it is not new to restrain the temperature of rolls by flowing water through their centers or axles; and also that 20 water circulating interiorly of rapidly driven fly wheels of speed motors and the like in chambers near their peripheries has been employed, I do not claim either of those methods or uses as novel in my invention *per se*, quite as the use of shafts, disks 25 or furnace chambers are not new *per se*; what I do claim for them as novel in their adaptation for use in my improved furnace will be clearly differentiated and set forth 30 specifically in my claims relative thereto, as hereinafter written.

With that in view attention is called to the fact that I prefer to use my improved hollow rollers as shown in Figs. 3 and 4 35 only at the front or charging end of my furnace adjacent to the entrance port 14, leaving the corresponding series of rollers near the exit or rear end of the furnace as being of solid disk construction with water 40 passages through their respective hubs only.

My said invention in that regard results in a most important improvement in the art of annealing said large plates in large furnaces, which would not be material in small 45 furnaces as now used where the interior is easily maintained at a practically uniform temperature, in that the rear rollers soon become much hotter than the forward rollers 50 and help raise the cooling rear ends of the plates and the back of the furnace to a temperature more nearly uniform with that of the entrance end; in that way making a correct annealing of said large plates alone 55 practicable.

In present practice when corresponding rolls or rollers have been superheated so as to have deteriorated it is necessary to shut down the furnace; tear its base apart and 60 substitute new rolls or rollers at very great loss of time and money.

Therefore I have provided the block beds 25, 25, as illustrated, and in practice, when renovation is needed, the outer ends of ports 65 26, 26 are opened; the successive block beds

25, 25 are pulled out therethrough in series; the shafts 9, 9, and with them the rollers 7, 7, are dropped down in the chambers 23, 23 to where said block beds were, and the rollers 7, 7, themselves are pulled out 70 through said ports 26, 26 and new ones substituted for them on the shaft members 9, 9; and the whole quickly reassembled for immediate use.

Having illustrated and described my inventions and improvements with such clearness that any one skilled in the art of furnace construction can build furnaces in conformity therewith and with modifications adapted to the specific classes of divers annealing furnaces without departing from my invention. 75

I claim:

1. The combination of an annealing furnace of the kind described and having an entrance port at the firing and charging end and an exit port at the opposite end; and rollers in a plurality of latitudinal series located at its bottom on revolute shafts below the line of said bottom a distance but 80 slightly less than the radii of said rollers; with chambers below said bottom opening at their tops thereinto and receiving said rollers; arches adjacent to the sides of said rollers, surmounting the lateral walls of said 85 chambers and protruding slightly into said furnace but less than do said rollers; bed blocks fitting into the bottoms of said chambers under said rollers, their hubs and portions of their sustaining shafts; and ports 90 at the sides of said furnace, in line horizontally with said bed blocks, positioned and of capacity for the withdrawal of said bed blocks, rollers and shafts therethrough, for the purpose set forth. 95

2. In a furnace of the kind described, having rollers mounted in latitudinal series on shafts below the bottom of said furnace and rotating in chambers in its base, bed blocks under said rollers substantially filling the portions of said chambers not occupied by said rollers, and lateral ports in line with the shafts of said rollers for the removal thereof therethrough for the purpose set forth. 100

3. In a furnace of the kind described, rollers positioned in series in a base at the bottom thereof and protruding a fraction of the length of their radii thereinto; lateral ports in the walls of said furnace in horizontal line with said series of rollers respectively and means for withdrawing said rollers through said ports as shown and described. 110

4. An annealing furnace having a hearth provided with transverse openings and with 125 charging and discharging openings at its respective ends in combination with means for moving articles through the furnace consisting of a series of shafts arranged transversely of the furnace and below the open- 130

ings in the hearth and each shaft carrying a plurality of spaced rollers, the shafts being located distances below the upper surface of the hearth less than the lengths of the radii of the rollers, whereby only small portions of the rollers will project above the hearth.

5. Rollers for receiving and transporting plates in an annealing furnace, rotated by hollow shafts, and having chambers leading to dead ends near the centers thereof, and to interior partition walls; thence

partly around their interiors near their peripheries to other oppositely disposed dead ends and the opposite faces of corresponding interior partition walls, and thence outwardly through the hubs of said rollers, as shown and described. 15

In testimony whereof I affix my signature in presence of two witnesses.

THOMAS J. COSTELLO.
